UNITED STATES PATENT OFFICE.

CLEMENT F. STREET, OF NEW YORK, N. Y., ASSIGNOR TO THE LOCOMOTIVE STOKER COMPANY, OF WILMERDING, PENNSYLVANIA, A CORPORATION OF PENNSYLVANIA.

MECHANICAL STOKER.

1,195,533.

Specification of Letters Patent. Patented Aug. 22, 1916.

Original application filed June 7, 1910, Serial No. 565,579. Divided and this application filed June 9, 1913. Serial No. 772,513.

To all whom it may concern:

Be it known that I, CLEMENT F. STREET, of the borough of Manhattan, in the city, county, and State of New York, have invented a certain new and useful Improvement 5 in Mechanical Stokers, of which improvement the following is a specification.

My invention relates to mechanical stokers 10 for feeding fuel to steam boiler fireboxes, and is designed for the purpose of enabling fuel, in the form of lumps or grains, or what is commercially termed slack, to be projected into the firebox by the direct action 15 upon it of a blast of fluid under pressure, and to be thereby distributed over the grate or bed where it is burned.

My improved stoker is designed with a 20 view of handling coal, coke, briquets or slack, and must be clearly distinguished from that class of stokers designed for handling pulverized or powdered fuel, which is burned in suspension and not on a grate or bed. For convenience, I will make use of the term 25 "lump fuel" hereinafter to designate the kind of fuel to be used in my stoker, in which term I include crushed coal, slack, briquets, and coke.

One of the objects of my invention is to 30 provide improved means for feeding fuel of the character above described into the furnace and distributing the same over the grate area by one or more fluid pressure operated distributing devices inserted through 35 openings in the furnace wall; and another object is to provide improved means for regulating the feeding of the fuel by controlling the admission of fluid pressure to the distributors.

40 The improvement claimed is hereinafter fully set forth.

In the accompanying drawings: Figure 1 is a rear elevation of a locomotive boiler 45 equipped with one form of mechanical stoker embodying my improvement; Fig. 2, a side elevation, partly in section, of the rear end of the locomotive boiler and stoker; Fig. 3, a vertical section of the fuel elevator and driving mechanism; Fig. 4, a vertical sectional view, on a larger scale, of the devices 50 for controlling the fluid under pressure;

Fig. 5, a vertical section of the controlling cam disk, taken on the line 5—5 of Fig. 4; Fig. 6, a side elevation, partly in section, of one of the side distributors; Fig. 7, an end view of the same; Fig. 8, a side elevation of the center distributor; Fig. 9, a transverse section of the same, taken on the line 9—9 of Fig. 8; and Fig. 10, a section of the end flange of the same, taken on the line 10—10 of Fig. 8.

According to the construction shown in the drawings, a fuel receptacle, 11, is located below the floor or deck of the cab, fuel being delivered thereto in any desired 65 manner, and an elevator is employed for raising the fuel therefrom to a conduit or hopper above the furnace door, said conduit communicating with one or more distributors discharging upon the furnace grate. 70

As shown, the elevator consists of an endless chain of buckets, 13, inclosed within a tubular casing, of inverted U-shape, the legs, 12, 12, of which terminate in the top of the fuel receptacle, 11, and extend upwardly on 75 opposite sides of the firing door, 6, and open into a fuel conduit or hopper, 18, located above said door.

The driving mechanism for the chain of buckets, 13, consists of a steam engine or 80 other motor, 16, mounted adjacent to the top of the casing, and driving through a worm or other gear, 17, (see Fig. 3), a sprocket wheel, 15, which engages said chain. The latter passes around guide wheels, 14, 85 14, mounted in the fuel receptacle, 11. As this elevator may be of any suitable well-known construction, it is unnecessary to describe it in further detail.

The elevator delivers the fuel into the conduit or hopper, 18, to the bottom of which are connected three distributors, 19, 19 and 20, which pass through the water-wall, 21, of the fire-box, 4, the distributor 20 being located centrally above said door and the 95 distributors, 19, 19, being located at the sides thereof. Where the furnace is of large dimensions, more than three distributors may be used, if desired, while, for small furnaces, only one or two distributors may 100 be used.

The center distributor, 20, is wholly or

partially obstructed or closed at its front end, which is provided with a rib, 22, located centrally between concavities, 21, 21, the end being inclined rearwardly from the 5 top downwardly, as shown in Figs. 8 and 10. Adjacent to its front end, this distributor has lateral apertures, 23, 23, which open downwardly and rearwardly toward the grate, the rib, 22, being continued along 10 the bottom of the distributor to a point in the rear of said apertures and having inclined sides, as shown in Figs. 8 and 9. Each of the side distributors, 19, 19, is open at its front end, the lower side, 24, of the 15 opening being inclined upward and straight, as shown in Figs. 6 and 7, and the upper side being extended, as shown, and having at its end a depending lug, 25, at right angles to the edge, 24, of the lower side of the 20 opening. By the construction described, the center distributor delivers the fuel to the rear portion and rear corners of the grate, while the side distributors feed it straight forward onto the sides of the grate, the lug, 25, causing the fuel to be spread somewhat laterally. Of course, the zones of the grate 25 onto which the fuel is deposited by the three distributors, are not finely demarcated, but overlap each other, so that there is a 30 fairly uniform distribution over the entire grate surface.

The rear end of each distributor is provided with two openings, the larger one, 27, being for the admission of air and the 35 smaller one, 28, communicating with a steam-pipe, 29, all of which pipes, 29, connect with a pipe, 30, leading from the steam space of the boiler, through the controlling valve, 32, (see Fig. 4). Of course, if desired, 40 compressed air may be used instead of steam. The valve proper, 31, is normally held to its seat by the steam pressure and by a spring, 33, thus shutting off the steam from the pipe, 30, leading to the pipes, 29. 45 The valve is opened intermittently by pressure applied to its stem, 34, and this is performed automatically by the cam-disk, 35, acting through the lever, 36, pivoted on a bracket, 37, on the valve-easing, and having a lug, 38, bearing against said valve-stem. Cam-disk, 35, is driven by the elevator motor, 16, in the instance shown being mounted directly on the shaft of the 50 sprocket wheel, 15. 55 Rotatably mounted within the cam-disk are two cam-members, 39, 39, each having two cam-surfaces, 40 and 41, the former being of less peripheral extent than the latter, and each having a handle, 42, by 60 which they can be rotated to bring either cam-surface into operative position, or so that neither cam-surface will project from the periphery of the disk. To hold each cam-member in any one of said three posi-

tions, it is provided with three recesses or 65 notches, 44, with any one of which a pawl, consisting of a flat spring, 45, with its end bent, can engage.

It will now be understood that the cam-disk, as it rotates, will either open the valve, 70 31, once or twice, and for a longer or shorter time, according as to which cam-surface is projected, or not at all when neither cam-surface is projected. Thus the fluid under pressure can either be cut off entirely from 75 the three distributors, when for any reason it is desired to stop the feed of the fuel by the fluid under pressure, or can be admitted to the distributors once in each rotation of the cam-disk, and that for a longer or shorter duration of time, according as to which cam-surface is projected, or the fluid can be admitted twice in each rotation of the disk, either for two short periods, two long periods, or for one short and one long 85 period.

While I have shown and described the cam disk as provided with only two identical cam members, each provided with two cam surfaces of different lengths, it will be obvious that more than two, or only one cam member may be provided on the disk, and that each cam member may have different cam-surfaces from the other, if desired.

A nozzle, 46, for the steam or other fluid 95 under pressure, is mounted in the opening, 28, at the rear end of each distributor. As this nozzle *per se* forms no part of my invention, it will be unnecessary to describe it 100 in detail.

Means are provided within the distributor hopper, 18, to vary the proportion of fuel fed to the several distributors. These comprise first, a regulator consisting of a plate, 47, slidably mounted in guides, 49, in the upper part of the hopper and actuated by a handle, 50, outside the same. When this plate is in its innermost position, the fuel is directed toward the opposite side distributor, 19, and practically none reaches the 110 adjacent side distributor. Second, of a V-shaped deflector, 51, slidably mounted, in guides, 52, directly over the open end of the center distributor, and operated from outside by a handle, 53. When this deflector is 115 pushed in, it prevents the fuel from entering the center distributor and at the same time deflects it laterally toward the side distributors. Of course, when it is partially in, it 120 also acts to deflect the fuel while, at the same time, permitting some of it to enter the center distributor. In this way, the supply of fuel to the individual distributors can be regulated and controlled. It must be understood that the fuel is not stored in the 125 hopper, 18, but that the latter acts merely as a conduit to guide and control the admission of the fuel to the distributors.

In operation, lump fuel is raised by the bucket elevator, 13, through one of the legs, 12, of the tubular U-shaped casing, and is delivered into the distributor hopper, 18, from which it falls by gravity into the three distributors, 19, 19 and 20, in amounts and proportion depending upon the adjustment of the slide, 47, and deflector, 51.

The controller-cam being set to admit 10 blasts of steam or other fluid at predetermined intervals and for longer or shorter periods into the pipes, 29, the fuel is intermittently projected from the distributors onto the grate in the manner above described. At the same time, there is no interference with the firing door, 6, so that the fireman can attend to the fire, and, if necessary, feed fuel to it by hand, as usual.

This application is a division of my original application Serial No. 565,579, filed June 7, 1910.

Having now described my invention, what I claim as new and desire to secure by Letters Patent is:

- 25 1. In a mechanical stoker of the type described, the combination with a source of fuel supply and a distributor connected thereto, of mechanism to admit fluid under pressure into said distributor periodically, a power device for driving said mechanism, and manually operable means to adjust said mechanism to vary the frequency of said admissions independently of the speed of the driving device.
- 30 2. In a mechanical stoker of the type described, the combination with a source of fuel supply and a distributor connected thereto, of power driven mechanism to admit fluid under pressure into said distributor periodically, the successive admissions being of different duration, and manually operable means to adjust said mechanism to vary the duration of the successive admissions after said adjustment.
- 35 3. In a mechanical stoker, of the type described, the combination with a source of fuel supply and a distributor connected thereto, of mechanism to admit fluid under pressure into said distributor periodically, a power device for driving said mechanism, and manually operable means to adjust said mechanism to vary the frequency and duration of said admissions independently of the speed of the driving device.
- 40 4. In a mechanical stoker, the combination of a distributor, power mechanism for admitting a continuous supply of fuel to said distributor, mechanism for intermittently admitting blasts of fluid under pressure to the distributor, a power device for driving said mechanism, and means for adjusting said mechanism to vary the frequency of said blasts.
- 45 5. In a mechanical stoker in which the

fuel is fed by fluid pressure, means to control the latter comprising a valve and a cam disk to operate the same, the cam surface of said disk being adjustable to vary the frequency of the operations of said valve.

6. In a mechanical stoker in which the fuel is fed by fluid pressure, means to control the latter comprising a valve and a cam disk to operate the same, the cam surfaces of said disk being adjustable to vary the frequency and duration of the operations of said valve.

7. In a mechanical stoker in which the fuel is fed by fluid pressure, means to control the latter comprising a valve and a cam disk to operate the same, the cam surfaces of said disk being adjustable to vary the frequency or duration or both the frequency and duration of the operation of said valve.

8. In a stoker of the type described, a distributor for feeding lump fuel into the furnace, said distributor having its delivery end provided with an obstruction and having lateral apertures adjacent to said end, said obstructed end being constructed with deflecting surfaces and adapted to divert the fuel rearwardly through said apertures.

9. In a mechanical stoker, a fluid pressure operated distributor having a closed end and lateral openings adjacent thereto, a concave upper surface between the openings, and a central deflecting rib on its bottom wall between the openings and extending up the end wall.

10. In a mechanical stoker, a fluid pressure operated distributor having a closed end wall and lateral openings adjacent thereto, a concave upper surface between the openings, and a central deflecting rib on its bottom wall between the openings, and extending up the end wall, the said end wall having lateral outwardly and rearwardly inclined ribs.

11. In a stoker of the type described, a distributor for feeding lump fuel into the furnace, said distributor having its delivery end provided with an obstruction having two concavities divided by a central rib, said end being open at the sides and said openings being separated at the bottom by a continuation of said rib.

12. In a mechanical stoker, a distributor for depositing the fuel upon the rear portion and onto the rear corners of the grate, said distributor having a rearwardly inclined front end provided with a central rib and lateral apertures adjacent to said end.

13. In a mechanical stoker, a distributor for depositing the fuel upon a longitudinal section of the grate, said distributor having its upper side extended beyond its lower side and the latter being inclined upward at its end and having a straight delivery edge, the upper side being provided with a

lug depending centrally at right angles to said straight edge.

14. In a mechanical stoker, a plurality of distributers for depositing lump fuel on the grate, the center distributer being constructed to direct the fuel rearwardly and laterally and the side distributers being constructed to deliver the fuel forwardly onto

the longitudinal side portions and toward the center of the grate.

In testimony whereof I have hereunto set my hand.
